DISPENSING CAP

Leonard M. Collins, Hollywood, Calif., assignor to Pres-
sure Dispensers, Inc., Los Angeles, Calif., a corpora-
tion of California

Application April 29, 1957, Serial No. 45,933

Term of patent 14 years

(Cl. D62—2)

Fig. 1

Fig. 2

Fig. 3

Fig. 4

Figure 1 is a perspective view of a dispensing cap embodying my new design, the valve being shown in its opened position;

Figure 2 is a side elevational view of the dispensing cap as shown in Figure 1;

Figure 3 is a side elevational view of the dispensing cap in closed position; and

Figure 4 is a top plan view of the dispensing cap.

The dominant features of my design reside in the por-
tions shown in full lines.

I claim:

The ornamental design for a dispensing cap, as shown
and described.
